US00D684564S

(12) **United States Design Patent**
Forster

(10) **Patent No.:** **US D684,564 S**
(45) **Date of Patent:** **** Jun. 18, 2013**

(54) **RFID ANTENNA**

(71) Applicant: **Avery Dennison Corporation**,
Pasadena, CA (US)

(72) Inventor: **Ian J. Forster**, Essex (GB)

(73) Assignee: **Avery Dennison Corporation**,
Pasadena, CA (US)

(**) Term: **14 Years**

(21) Appl. No.: **29/434,366**

(22) Filed: **Oct. 12, 2012**

(51) LOC (9) Cl. **14-03**

(52) U.S. Cl.

USPC **D14/230**

(58) **Field of Classification Search**

USPC D14/138, 230-238, 299, 358; D12/42,
